UNITED STATES PATENT OFFICE.

ASA ASHWORTH, OF SALAMANCA, NEW YORK.

APPARATUS FOR DYEING TOPS, YARN, &c.

1,374,628.

Specification of Letters Patent. Patented Apr. 12, 1921.

Application filed October 15, 1920. Serial No. 417,081.

To all whom it may concern:

Be it known that I, ASA ASHWORTH, a citizen of the United States, residing at the town of Salamanca, in the county of Cattaraugus and State of New York, have invented certain new and useful Improvements in Apparatus for Dyeing Tops, Yarn, &c., of which the following, taken in connection with the accompanying drawings, is a specification.

The invention relates to the holding of tops or yarn in such density and under proper control to permit the passage of dyeing or mordanting liquids or gases back and forth through said tops or yarn to attain more perfect and permanent coloring of the same, and the exhaustion of the coloring matter from the dye; and the improvement consists in providing a non-collapsible reel or spool which may be placed one above the other and the series become collectively collapsible or telescoping, and toward this end each of said spools is made tubular and tapering or funnel-shaped so as to be insertible one within the other, the smaller ends being invariably placed downward, said spools having openings therein, either perforate or slotted, or woven wire, and of sufficient size so that the tops, yarn, etc., can be wound on the same and the loaded spools may be placed one upon the other upon the perforate tubular nozzles or spindles through which the dye is forced, a weight being provided for the top of the series to press said loaded spools downward, each of said funnel-shaped reels or spools extending into the upper end of the spool below so that the mass of yarn or tops on the series of loaded reels or spools is pressed to the required density and the liquid dye or gases cannot seek and find a line of least resistance and flow through such channels or passages, but they are forced out evenly through the entire mass, thereby attaining an even and more perfect action of said dyeing or mordanting liquid or gases, means being provided for reversing the direction of said liquids or gases so that the same dye or gas may be forced outward and then withdraw back through the mass of yarn or tops a number of times until the coloring matter in the dye is substantially exhausted; and the invention consists in the novel features and combination hereinafter set forth and claimed.

In the drawings Figure 1 is a crosswise

sectional perspective of the preferred form of one of the dyeing vats showing the dye receiving and distributing compartment in the base of said vat, and the perforate nozzles or spindles extending up from the same into the dyeing chamber, which spindles are loaded with the spools of yarn, tops, etc., portions of the mass of yarn and tops being shown in section on one spindle, a second spindle being only partially loaded, and the third spindle having the heavy top weight in section, the heavy top of the dyeing vat being broken away, a quarter of said top being shown. Fig. 2 is an elevation of the slotted form of the tapered or funnel-shaped spool or reel; and Fig. 3 is a similar elevation of the perforate form of said spool or reel; and Fig. 4 is a similar view of the woven wire form of said reel or spool, a middle portion of the length of each of said reels or spools being broken away to show both ends of the same. Fig. 5 is a sectional view of one of the perforate nozzles or spindles in the dyeing vat, portions of the top and bottom of said vat being shown in section and the series of loaded reels or spools on the nozzle being also shown in section. Fig. 6 is a lengthwise sectional view of one of the tubular perforate spools or reels in the preferred proportion for the same; and Fig. 7 is a top plan view of said spool or reel. Fig. 8 is an elevation of a loaded spool ready for inserting the nozzle therethrough for arrangement in series.

Like characters of reference refer to corresponding parts in the several views.

The numeral 10 designates the reel or spool which is preferably made of one piece of sheet metal having slots 11 as shown in Fig. 2, or having perforations 12 as shown in Fig. 3, being preferably made with a wire or other binder 13 at the top and bottom, the perforations or slots being sufficient for the free passage of the dyeing or mordanting liquids or gases back and forth through the sides of said reels or spools.

A modification of the preferred sheet metal reel or spool is shown in Fig. 4, in which the tubular funnel-shaped reel or spool is made from a single sheet of fairly heavy, non-corrosive or non-rusting woven wire 14 in which the mesh is sufficiently coarse for the dyeing or mordanting liquid gases to pass freely back and forth through the same, and yet to hold the yarn or tops firmly in position without drawing through

22 said mesh to thereby impair the material and the action of said liquids and gases. The adjacent edges of the woven wire are attached to one another in any suitable manner to hold with great strength, and the top and bottom have preferably a brass or non-corrosive or non-rusting binding 14' which holds the edges of the woven wire firmly in shape when a series of the woven wire reels or spools are pressed one into the other.

Whether said reels or spools are made from the sheet metal or the woven wire, it is apparent that the single sheet formed in 15 the tubular tapered funnel shape with protected upper and lower edges makes a strong and exceedingly economical non-collapsible reel or spool of such design or shape that a series of said funnel-shaped spools shutting into one another is telescoping or collapsible, thereby making a stronger and simpler spool and attaining the end desired at 20 a much lower cost than if each spool or reel were made collapsible.

25 The spools or reels are preferably made about sixteen inches in length, and where the perforated spindles or nozzle pipes 15 in the dye vat or tub 16 are two inches in diameter, then the lower end of the funnel-shaped reel or spool 10 is preferably about 30 two and one-fourth inches in diameter, while the upper end is about three and one-fourth inches, that is, making about one 35 inch difference in the diameter of the opening within the ends of the funnel-shaped spool or reel, though for different purposes these dimensions may be varied without departing from my invention.

The dye tub or vat 16 preferably has a 40 receiving and distributing compartment 17 at the bottom of the same formed by the two spaced bottoms 18 and 19 into which compartment the dye or mordanting liquid or gases are forced through the pipe 20, 45 which pipe 20 extends down to a reversible or two-way valve 21, thence through a pipe 22 and pump 31 to the opposite side of the valve 21, and thence out through a pipe 23 to a reservoir 24, the pipe 25 leading from 50 said reservoir to the interior of the upper end of the dyeing compartment 26 within the tub or vat 16.

A plurality of perforate nozzles or spindles 15 are provided in the compartment 55 26 in the tub 16 which extend through the upper bottom 18 into the receiving compartment 17 for the dye or mordanting liquid so that when said liquid or gases have received sufficient pressure, they are forced 60 up through the spindles or nozzles 15 and out through the tops or yarn 27 wound on the spools 10 into the compartment 26 of the vat or tub 16, a suitable pump 31 being provided in connection with said pipes and 65 reservoir to force the liquid preferably first

into the compartment 17, through the pipe 20 and up through the spindles 15 and out into the compartment 26 until said compartment is filled, after which the valve 21 is reversed and the pump 31 draws the liquid or gases from the reservoir 24 through the pipe 25 and from the compartment 26 back through the yarn or tops 27 to the reservoir 24. This reversal of the direction of the dye or mordanting liquids or gases is usually reversed from six to eight times until all the coloring matter in the dye or strength in the mordanting liquid is substantially exhausted and the fiber of the yarn or tops is thoroughly impregnated with said dye or mordanting liquid or gases.

The perforate spindle or nozzle 15 is preferably formed with a top closure plug 28 and a heavy weight 29 is provided having a hole therein to place on the top of the 85 series of loaded reels or spools and press the mass of yarn or tops downward to the required density and when in place, the heavy closure top 30 of the tub or vat 16 is dropped onto the top of said tub, usually 90 resting upon the top of said weights 29 of the different loaded spool series, holding the same in place. As said liquid or gases are forced back and forth through the mass of tops or yarn, the same gradually collapse 95 pressed downward by the heavy weight 29.

The uniform density of the tops or yarn attained under compression in this process of dyeing also achieves an additional utility, 100 besides that of even dyeing of the fiber in that it is non-felting, since there is no frictional flow of the dyeing liquid over or through the mass of tops or yarn, but rather a gradual permeation of said mass by said liquid as it is forced out through the mass 105 of yarn or tops, or drawn back through the same to or from the spindle or nozzle 15, said simple tubular reels or spools holding the yarn or tops wound thereon without separation as they press upon one another. 110

What is claimed is:

1. An apparatus for dyeing tops and yarn comprising a dyeing vat, a perforate tube vertically mounted in said dyeing vat, means for forcing fluid dye or mordant through 115 said tube, and a series of collectively collapsible tubular yarn spools mounted upon said tube.

2. An apparatus for dyeing tops and yarn comprising a dyeing vat, a cover for said 120 vat, a distributing compartment in the bottom of said vat, means for forcing liquid into and withdrawing same from said compartment in the bottom of said vat under pressure, a series of perforated tubes in said 125 vat opening into said compartment in the bottom thereof to force said dye through said tubes, a plurality of tubular tapered perforate yarn spools for said yarn or tops insertible in one another to collectively col- 130

lapse the same, said spools mountable in series upon said tubes.

3. In a dyeing apparatus, a perforated tubular support, means to force dye through the perforations of the support, and a series of yarn carrying spools on the support, said spools being of upwardly flaring formation so that the smaller ends of the upper spools are receivable within the larger ends 10 of the adjacent lower spools.

4. In a dyeing apparatus, a foraminous tubular support, a series of telescopic yarn carrying spools on the support receivable one within the other throughout a considerable portion of their lengths, means to force 15 dye through the perforations of the support, and a weight acting on the uppermost spool to continuously force same downwardly.

5. In a dyeing apparatus, a perforated 20 tubular support, a series of yarn carrying spools thereon, said spools being formed so as to enable same to collapse throughout a considerable portion of the lengths thereof

and means to force dye through the support perforations.

6. In a dyeing apparatus, a perforated tubular support, a series of collapsible yarn carrying spools thereon, means to force dye through the perforations of the support, and a weight resting on the uppermost yarn 30 carrying spool and guidingly engaged with the support.

7. In a dyeing apparatus, a vertical support, and a series of yarn carrying spools received over the support, said spools being 35 of upwardly flaring formation and having their smaller lower ends guidingly engaged with the support and received in the larger upper ends of the adjacent lower spools to allow the spools to telescope.

In testimony whereof I have affixed my signature in the presence of two witnesses:

ASA ASHWORTH.
